UNITED STATES PATENT OFFICE.

LAURA BAVRY, OF CHICAGO, ILLINOIS.

DESIGN FOR A VEGETABLE-CHOPPER.

SPECIFICATION forming part of Design No. 33,983, dated January 29, 1901.

Application filed January 2, 1901. Serial No. 41,913. Term of patent 7 years.

To all whom it may concern:

Be it known that I, LAURA BAVRY, a citizen of the United States, residing at Chicago, Illinois, have invented and produced a certain new and original Design for Vegetable-Choppers, of which the following is a specification.

The invention relates to a new and original design for vegetable-choppers; and it consists of a design of the shape and configuration shown in the accompanying drawings, in which—

Figure 1 is a perspective view of the chopper, and Fig. 2 is a bottom plan.

The leading feature of the design comprises an annular scalloped cutter-body of uniform diameter from top to bottom, the same consisting of a series of integral alternate con-

vex and concave walls A and B, respectively, whereby each of the edges of the cutter-body presents a connected series of oppositely-disposed graceful curves, and the appearance of sharp or acute angles is avoided.

Secured to opposite points on the upper edge of the cutter-body is an arc-shaped bridge C, from the center of which rises a handle D.

What I claim is—

The design for a vegetable-cutter as herein shown and described.

In testimony whereof I have hereunto set my hand in the presence of two subscribing witnesses.

LAURA BAVRY.

Witnesses:

FREDERICK C. GOODWIN,
SAMUEL N. POND.
